U.S. Appl. No. 29/289,257, filed Jul. 13, 2007.

* cited by examiner

Primary Examiner—Ian Simmons*Assistant Examiner*—Elizabeth J Oswecki(74) Attorney, Agent, or Firm—Fross Zelnick Lehrman & Zissu, P.C.; Lawrence E. Apolzon, Esq.(57) CLAIM

The ornamental design for a jewelry item, as shown and described.

DESCRIPTION

FIG. 1 is a front perspective view of a jewelry item showing my new design;

FIG. 2 is a left side view thereof;

FIG. 3 is a right side view thereof;

FIG. 4 is a front view thereof; and,

FIG. 5 is a top view thereof.

The broken line showing of a toe of a shoe is included for the purpose of illustrating only and forms no part of the claimed design.
